(57) **CLAIM**

The ornamental design for a rear grill for skid steer loader, as shown and described.

DESCRIPTION

FIG. 1 is a perspective view of a rear grill for skid steer loader showing our new design in its environment;

FIG. 2 is a front perspective view thereof;

FIG. 3 is a cross-sectional view thereof taken along the line 3—3 in FIG. 1; and,

FIG. 4 is a rear perspective view thereof.

The broken line showing in FIGS. 1, 3, and 4 is for illustrative purposes only and forms no part of the claimed design.
